PICTURE FRAME MOULDING

Johannes Vihma, Toronto, Ontario, Canada, assignor to
Artistic Woodwork Co., Ltd., Downsview, Ontario,
Canada

Filed May 16 1975, Ser. No. 578,326

Term of patent 14 years

Int. Cl. D6—07

U.S. Cl. D6—246

FIG. 1

FIG. 2

FIG. 1 is a front perspective view of a picture frame moulding showing my new design, a portion thereof being broken away to indicate indeterminate length; and

FIG. 2 is a rear perspective view thereof.

I claim:

The ornamental design for a picture frame moulding, as shown and described.
